UNITED STATES PATENT OFFICE.

WILLIAM E. DELEHANTY, OF NEW YORK, N. Y.

SOIL-PIPE CONNECTION FOR CLOSET-BOWLS.

No. 800,083.

Specification of Letters Patent.

Patented Sept. 19, 1905.

Application filed August 8, 1903. Serial No. 168,733.

To all whom it may concern:

Be it known that I, WILLIAM E. DELEHANTY, a citizen of the United States, residing in New York city, county of New York, State of New York, have invented certain new and useful Improvements in Soil-Pipe Connections for Closet-Bowls; and I do hereby declare the following to be a full, clear, and exact description of the invention, such as will enable others skilled in the art to which it appertains to make and use the same.

My invention relates to certain new and useful improvements in soil-pipe connections for water-closet bowls, and is designed to provide a convenient, practical, and efficient device for that purpose.

In the accompanying drawings, Figure 1 represents a soil-pipe connection embodying my invention, the parts (including the soil-pipe and the closet-bowl) being shown in vertical section. Figs. 2 and 3 represent, respectively, on a larger scale, a top plan view and a bottom plan view of the floor-plate constituting one of the elements of the joint.

Similar letters of reference indicate similar parts throughout the several views.

Referring to the drawings, A indicates a water-closet bowl of approved type, B indicates the soil-pipe, and C indicates the floor-plate.

The floor-plate C surrounds the upper portion of the soil-pipe and is provided with an annular flange *a*, having a sealing-seat on its upper periphery and adapted to make contact with the packing-ring *c*, of prepared asbestos or the like. The seat of the flange is provided with an annular groove *b* rendering it particularly sensitive when brought into contact with the packing, which is forced into the groove, thereby rendering the joint additionally secure. The flange *a* is also beveled at *d*, as shown, to receive molten solder which on cooling unites the floor-plate to the soil-pipe.

The closet-bowl A is provided with a hollow spud or projection *e* entering the soil-pipe and is likewise provided with a base having a recess for the reception of the packing-ring *c* and having a foot-flange *f*. The purpose of this outlying foot-flange is to inclose the floor-

plate, thereby concealing it from view and also to take the weight of the bowl off the floor-plate, except at the grooved seat, to which end the flange *f* is made sufficiently high to leave a substantial clearance between the outer rim of the floor-plate and the lower surface of the base. The joint or connection is completed by means of screw-threaded bolts and nuts. The heads *g* of the bolts engage the floor-plate and the shanks of the bolts pass through apertures in the base of the bowl and receive at their ends the washers *h* and nuts *i*. To receive the heads of the bolts, the floor-plate rim is provided with openings sufficiently large at *k* to permit the bolt-head to pass through, but beveled at *l* and of lesser width, so that the bolt-heads will engage the beveled surfaces when in place therein. This construction is of particular importance should it be desired for any reason to remove the bowl, as in case of injury to the bowl itself or to its base. In such event it is merely necessary to slack up the nuts *i*. The bolts, may then be shifted laterally until their heads pass from the narrow portions *l* into the wider portions *k* of the floor-plate openings, whereupon the bowl, together with the bolts, may be lifted without disturbing the floor-plate or its solder joint. Conversely, a new or substitute bowl may be connected up to the soil-pipe, the heads of the bolts passing through the openings *k* and the bolts being then shifted until their beveled heads enter the beveled openings *l*.

It will be noted that the hollow spud or projection *e* is of such length that its lower edge is on a level with the lower edge of the flange *f*. This is of particular advantage in finishing the base, for the reason that these edges can both be ground and trued off at the same operation and by the same grinding-wheel, with corresponding saving of time and economy.

Having thus described my invention, what I claim is—

A soil-pipe connection for closet-bowls, comprising a floor-plate connected to the upper end of the soil-pipe and having an annular flange provided on its top with a grooved seat, a packing-ring engaging said

95

100

seat, a closet-bowl having a base provided with a tubular projection entering the soil-pipe and having a depending flange within which the packing-ring is held and centered, 5 and having also an outside flange inclosing the floor-plate, and relieving it from the pressure of the bowl except at the grooved seat, and means for drawing the floor-plate and

base together to complete the joint; substantially as described.

In testimony whereof I affix my signature in presence of two witnesses.

WILLIAM E. DELEHANTY.
